DESIGN FOR A DISPENSING CLOSURE

Herman H. Martin, Toledo, Ohio, assignor to H. H. Martin Products Corporation, Toledo, Ohio, a corporation of Ohio

Application May 22, 1939, Serial No. 85,117

Term of patent 14 years

To all whom it may concern:

Be it known at I, Herman H. Martin, a citizen of the United States, residing at Toledo, Lucas County, Ohio, have invented a new, original, and ornamental Design for a Dispensing Closure, of which the following is a specification.

The design is shown in the accompanying drawing, which forms a part thereof, and in which:

I claim:

The ornamental design for a dispensing closure, substantially as shown.

HERMAN H. MARTIN,
